WIRE REELING ATTACHMENT FOR
TRACTORS

John E. Foran, Bement, Ill.

Application January 23, 1948, Serial No. 3,960

7 Claims. (Cl. 242—93)

1

This invention relates to wire reeling and unreeeling machines and is more particularly directed to reeling attachments securable to and operable by farm tractors.

The object of this invention is to provide a simple and inexpensive wire reeling and unreeeling mechanism readily securable to the frame of a farm tractor and operated from the belt pulley thereof so that barbed or other wire may be readily reeled and unreeled and which provides a simple manually-operated control to distribute the wire on the reel during the reeling operations.

In the drawings:

Fig. 1 is a plan view of the reeling and unreeeling attachment.

Fig. 2 is a side elevational view thereof.

Fig. 3 is a sectional view taken substantially along the line 3—3 of Fig. 2.

Fig. 4 is a sectional view taken substantially along the line 4—4 of Fig. 3; and

Fig. 5 is a view taken substantially along the line 5—5 of Fig. 2.

Referring now to the drawings, numeral 1 designates a portion of one of the frames of the tractor chassis to which a fixture 2 is securable. This fixture has a spindle 3 suitably secured thereto on which a pulley wheel 4 is rotatably mounted that is provided with a hub 5. The hub has a plurality of slots formed therein which are adapted to be engaged by suitable prongs 6 that are formed on a sleeve 7 rotatable on the spindle 3, the prongs 6 being insertable in the slots in the pulley wheel 4 in order that the two will be connected together. A suitable reel 8 is mounted on the sleeve 7 in a manner to rotate therewith. The prongs 6 are held in the slots in hub 5 by means of a spring 9 fitted on the spindle 3, one end of which engages a washer 10 which has a friction element 11 associated therewith that is in engagement with a washer 12 operatively associated with the sleeve 7. The sleeve 7 may be appropriately shaped, if desired, to form a cooperating face for the friction element 11. The spring 9 is placed in compression by means of a sleeve 13 that fits over the end of the spindle 3 and is held in adjusted position by means of a pin 14 insertable in a plurality of diametrical bores 15 formed in the outer end of the spindle 3, thereby enabling the tension of the spring 9 to be varied at will.

A stationary guide 16 is suitably secured to the tractor frame 1 and has a plurality of spaced rollers 17 mounted therein. The rollers nearest each other serve as wire guides and the others serve as spacers. A lever 18 is pivoted to the outer end of the frame 16 and is also pivoted to the

2

sleeve member 13, thereby constituting an outboard support for the spindle 3. The rollers 17 are so spaced that they define the limits of the reel 8 so that wire will be confined to the winding space on the reel 8.

Wire is guided across the reel 8 as it rotates by means of a guide mechanism 19 in which a plurality of rollers 20 are rotatably mounted. Two of the rollers 20 are mounted close together between which the wire is passed for guiding the wire so that the tractor operator may have better control thereover. The other rollers on guide 19 serve as spacers. The guide 19 is supported on one end of a lever 21 that slides in slot 16' in guide 16 and is pivotally supported on a bracket 22 that is a part of the fixture 2. The opposite end of the lever 21 extends to a position adjacent the tractor operator's station so that he can conveniently guide the wire back and forth across the reel 8.

The pulley 4 is connected to the tractor pulley by means of a belt 23 during reeling operations, the tractor being driven at a suitable speed so that the wire can be properly wound on the reel 8.

This mechanism is also employable as a wire unreeeling device but during this operation the belt 23 is not employed and the tractor is then driven at a suitable speed. In order to prevent excessive unwinding of the reel, the friction element 11 acts as a brake for the reel 8 in order to prevent too rapid unwinding of the wire reel.

This mechanism provides a convenient and simple mechanism employable for both reeling and unreeeling operations and which may be quickly attached to and detached from an ordinary farm tractor to thereby materially expedite the building of barbed wire fences and the reeling of barbed wire when they are taken down.

What I claim is:

1. A wire reeling attachment for a tractor frame comprising a spindle; means for securing said spindle to the frame of the tractor so that the spindle projects from the frame; a pulley rotatably mounted on said spindle; a reel supporting sleeve rotatably mounted on said spindle and engageable with said pulley; means to urge said sleeve into engagement with said pulley; a stationary wire guide supported on the tractor frame; a movable wire guide; a lever to move said movable guide and operatively associated with said stationary guide, said movable guide threading wire across said reel and said stationary guide confining the wire threading within the length of said reel; and a lever connected between said

stationary guide and said means to provide an outboard support for said spindle.

2. A wire reeling attachment for a tractor frame comprising a fixture securable to the frame of the tractor; a spindle associated with said fixture and projecting from the frame; a pulley rotatably mounted on said spindle; a reel supporting sleeve rotatably mounted on said spindle; means to urge said sleeve into engagement with said pulley; a stationary wire guide mounted on the tractor frame; a movable wire guide; a lever operatively associated with said stationary guide and on which said movable guide is mounted, said movable guide threading wire across said reel and said stationary guide confining the wire threading within the length of said reel; means associated with said fixture on which said lever is pivotally supported; and a lever connected between said means and said stationary guide to provide an outboard support for said spindle.

3. A wire reeling attachment for a tractor comprising a fixture securable to the frame of the tractor; a spindle associated with said fixture and projecting from the frame; a pulley provided with a hub having apertures therein and rotatably mounted on said spindle; a reel supporting sleeve rotatably mounted on said spindle and provided with means to engage said apertures; means to urge said sleeve into engagement with said pulley; a stationary wire guide mounted on the tractor frame; a movable wire guide; a lever operatively associated with said stationary guide and on which said movable guide is mounted, said movable guide threading wire across said reel and said stationary guide confining the wire threading within the length of said reel; means associated with said fixture on which said lever is pivotally supported; and a lever connected between said means and said stationary guide to provide an outboard support for said spindle.

4. A wire reeling attachment for a tractor comprising a spindle securable to the frame of the tractor; a spindle associated with said fixture and projecting from said frame; a pulley rotatably mounted on said spindle; a reel supporting sleeve rotatably mounted on said spindle and engageable with said pulley; means to urge said sleeve into engagement with said pulley; a stationary wire guide supported on the tractor frame; a movable wire guide; a lever to move said movable guide and operatively associated with said stationary guide, said movable guide threading wire across said reel and said stationary guide confining the wire threading within the length of said reel; a lever connected between said stationary guide and said means to provide outboard support for said spindle; and means associated with said sleeve to retard reel rotation during unwinding operations of said reel.

5. A wire reeling device comprising a spindle securable to the frame of the tractor and projecting from the frame; a pulley rotatably mounted on said spindle; a reel supporting sleeve rotatably mounted on said spindle and engageable

with said pulley; means adjustably mounted on said spindle to urge said sleeve into engagement with said pulley; a stationary wire guide supported on the tractor frame; a movable wire guide; a lever operatively associated with said stationary guide to move said movable guide, said movable guide threading wire across said reel and said stationary guide confining the wire threading within the length of said reel; and a lever connected between said stationary guide and said means to provide outboard support for said spindle.

6. A wire reeling attachment for a tractor comprising a fixture securable to the frame of the tractor; a spindle associated with said fixture and projecting from the frame; a pulley provided with a hub having apertures therein and rotatably mounted on said spindle; a reel supporting sleeve rotatably mounted on said spindle and provided with means to engage said apertures; a stationary wire guide mounted on the tractor frame; a movable wire guide; a lever operatively associated with said stationary guide and on which said movable guide is mounted, said movable guide threading wire across said reel and said stationary guide confining the wire threading within the length of said reel; means associated with said fixture on which said lever is pivotally supported; and a lever connected between the unsupported end of said spindle and said stationary guide to provide outboard support for said spindle.

7. A wire reeling device comprising a spindle securable to the frame of the tractor and projecting from the frame; a pulley rotatably mounted on said spindle; a reel supporting sleeve rotatably mounted on said spindle and engageable with said pulley; means adjustably mounted on said spindle to urge said sleeve into engagement with said pulley; a stationary wire guide supported on the tractor frame; a movable wire guide; a lever operatively associated with said stationary guide to move said movable guide, said movable guide threading wire across said reel and said stationary guide confining the wire threading within the length of said reel; a lever connected between said stationary guide and said means to provide outboard support for said spindle; and means associated with said reel to retard reel rotation during reel unwinding operation.
